(57) **CLAIM**

We claim the ornamental design for a pool fence screen secured with hook and loop material, as shown and described.

DESCRIPTION

FIG. 1 is a perspective view of the invention taken from the front to the left and above the invention showing a wave line decoration.

FIG. 2 is an exploded perspective view of the invention taken from the front, to the left and above the invention.

FIG. 3 is a front elevation view of the invention.

FIG. 4 is a rear elevation view of the invention.

FIG. 5 is a right side view; and,

FIG. 6 is a top view of the invention.

The left side view is not shown because it is identical to the right side view shown in FIG. 5.

The bottom view is not shown because it is identical to the top view shown in FIG. 6.
